R. L. FRYE

RAIL JOINT

Filed March 3, 1928

INVENTOR
Robert L. Frye
BY
William A. Hughes
ATTORNEY

UNITED STATES PATENT OFFICE.

ROBERT L. FRYE, OF DUNBAR, PENNSYLVANIA.

RAIL JOINT.

Application filed March 3, 1928. Serial No. 258,727.

The present invention relates, generally, to rail joints, and, more particularly, to means for clamping and holding together the abutted ends of rails as in a track.

5 An object of the invention is to provide a light, strong, easily applied and economical rail joint clamp.

Other objects and advantages of the invention will appear from the following description of an illustrative embodiment thereof, and from the drawing illustrating the same, and from the accompanying claims; and the invention consists in the new and useful arrangements and combinations of devices and parts set forth in the accompanying claims.

The invention is clearly illustrated in the drawing, in which:

Figure 1 is a longitudinal elevation view 20 of the device of the invention in place on a railroad track;

Figure 2 is a similar view but taken from the side opposite to that shown in Figure 1;

Figure 3 is a sectional view taken along 25 the line 3—3 of Figure 1, looking in the direction of the arrows; and

Figure 4 is a sectional view taken along the line 4—4 of Figure 1, looking in the direction of the arrows.

30 In all the above described views like reference characters are used throughout to indicate corresponding parts.

In the drawing the railroad tie 10 carries, in end abutting relation, the track rails 12 and 14. Against one side of said abutted rails 12 and 14 and overlapping both of them is the angular fish plate 16 which lies against the web and the base thereof. Opposite said plate 16 a second fish plate 18 lies against the web and base. The fish plate is tapered from the middle toward each end, having outer surfaces at an obtuse angle to each other. Each of said plates 16 and 18 has a notch 20 centrally disposed at its lower edge and adapted to receive a rail spike 22 for holding the respective plates against longitudinal movement from said tie 10, but allowing lateral movement thereof toward said rails 12 and 14. A pair of narrow saddles 24, 24, one near each end of said plates 16 and 18, extend from engaging relation with the lateral surface of said plate 16, through respective notches 26, 26 in the bottom edge of said plate 16, around under the base of a respective one of said rails 12 and 14, and through the notches 28, 28 in said

plate 18 thence upwardly with an inwardly offset lug 30 in spaced apart relation above the bottom portion of said plate 18 and in spaced apart relation with the side portion 60 thereof.

Under a respective one of said lugs 30 and one between each of said saddles 24, 24 and the respective tapered lateral surface of said fish plate 18 is a wedge 32 having an inner face tapered to fit the tapered face of said plate 18 adjacent thereto and having an outer face which can be parallel to said rails 12, 14 or slightly inclined to converge inwardly with said inner tapered face. As 70 means for drawing said two wedges 32, 32 toward each other there is provided the bolt 34 one end having a left hand thread and the other a right hand thread, one end being threaded through one of said wedges 32 and the other through the other. A fixed central lug 36 on said bolt 34 serves for turning it to draw said wedges 32, 32 together or to spread them apart. Lock nuts 38, 38, one adjacent each of said wedges 32, 32, serve to lock said bolt 34 against turning when desired. By turning said bolt 34 to draw said wedges 32, 32 together, said fish plates 16 and 18 are tightly clamped against the sides of said rails 12 and 14 to hold them 85 together in tightly locked relation. With the nuts 38, 38 tightly against the respective ones of said wedges 32, 32 the fish plates can be held against any creeping or jarring 90 loose such as occurs in other devices through vibration produced when trains pass over the rails or by expansion and contractions due to changes in temperatures. On the other hand the device can be quickly loosened and reset to relieve the rails of strains 95 caused by expansion or contraction.

I am aware that various changes, and omissions and substitutions, other than those above noted, can be made in device of the invention as illustrated and described without departing from the scope of the invention as set forth in the appended claims.

Having thus described my invention, what I claim as new and desire to secure by Letters Patent is:—

1. In a rail connection adapted for use with the meeting ends of two rails; the combination of a pair of opposed clamping members, one for each side of said meeting rails; one of said clamping members having outer surfaces which are at an obtuse angle to each other and which are inclined from

the middle toward each end; a pair of wedges one at each of said inclined surfaces; a pair of saddles, adapted to extend one from each of said wedges around, under the 5 rails, and into engaging relation with the clamping member on the side opposite said inclined clamping member.

2. In a rail connection adapted for use with the meeting ends of two rails; the 10 combination of a pair of opposed clamping members, one for each side of said meeting rails; one of said clamping members having outer surfaces which are at an obtuse angle to each other and which are inclined 15 from the middle toward each end; a pair of wedges one at each of said inclined surfaces; a pair of saddles, adapted to extend one from each of said wedges around, under the 20 rails, and into engaging relation with the clamping member on the side opposite said inclined clamping member, and means for moving said wedges into wedging relation with their respective saddles.

3. In a rail connection adapted for use 25 with the meeting ends of two rails; the combination of a pair of opposed clamping members, one for each side of said meeting rails; one of said clamping members having outer surfaces which are at an obtuse angle 30 to each other and which are inclined from the middle toward each end; a pair of wedges one at each of said inclined surfaces; a pair of saddles, adapted to extend one from each of said wedges around, under

the rails, and into engaging relation with 35 the clamping member on the side opposite said inclined clamping member; and a bolt, having a left hand thread and a right hand thread, one extending in threaded relation in each of said wedges, adapted to draw said 40 wedges toward each other and to move them apart.

4. In a rail connection adapted for use with the meeting ends of two rails; the combination of a pair of opposed clamping 45 members, one for each side of said meeting rails; one of said clamping members having outer surfaces which are at an obtuse angle to each other and which are inclined from the middle toward each end; a pair of 50 wedges one at each of said inclined surfaces; a pair of saddles, adapted to extend one from each of said wedges around, under the rails, and into engaging relation with the clamping member on the side opposite said 55 inclined clamping member; and a bolt, having a left hand thread and a right hand thread, one extending in threaded relation in each of said wedges, adapted to draw said wedges toward each other and to move them apart, said bolt having a turning lug or head thereon and lock nuts in operative relation to each of said wedges.

In testimony, that I claim the invention set forth above I have hereunto set my hand 60 this 20th day of February, 1928. 65

ROBERT L. FRYE.
